ELECTRONIC SIGNAL GENERATOR FOR MUSCLE STIMULATION

Logan D. Gilman, St. Paul, Minn., assignor to Theratron
Corporation, St. Paul, Minn., a corporation of Minne-
sota

Filed Sept. 20, 1961, Ser. No. 66,775

Term of patent 14 years

(Cl. D83—1)

FIG. 1 is a view in top plan of an electronic signal generator for muscle stimulation, showing my new design;

FIG. 2 is a view in bottom plan thereof;

FIG. 3 is a view in side elevation thereof;

FIG. 4 is a view in elevation as seen from left to right of FIG. 1; and

FIG. 5 is a view in elevation as seen from right to left of FIG. 1.

The dominant features of my design reside in the portions shown in full lines.

I claim:

The ornamental design for an electronic signal generator for muscle stimulation, as shown and described.
